UNITED STATES PATENT OFFICE.

FRANK P. WILLIAMS, OF DETROIT, MICHIGAN, ASSIGNOR TO E. E. GUDKA MFG. CO.,
OF DETROIT, MICHIGAN, A CORPORATION OF MICHIGAN.

FAUCET ATTACHMENT.

1,395,322.

Specification of Letters Patent.

Patented Nov. 1, 1921.

Application filed May 21, 1920. Serial No. 383,038.

To all whom it may concern:

Be it known that I, FRANK P. WILLIAMS, a citizen of the United States, residing at Detroit, in the county of Wayne and State 5 of Michigan, have invented certain new and useful Improvements in Faucet Attachments, of which the following is a specification.

This invention relates to combined drinking fountains and filters, and comprises an attachment which can be very cheaply manufactured largely out of sheet metal and which is intended to be applied to an ordinary faucet or bib. The normal action of 10 the device is to filter the water, but when desired, a button may be pressed to convert the attachment into a bubbling fountain for drinking. This will more fully appear in the description following.

20 In the drawings,—

Figure 1 is a side elevation.

Fig. 2 is a plan view of the attachment.

Fig. 3 is a vertical section of the attachment upon a faucet.

25 Fig. 4 is an enlarged vertical section.

a represents a sheet metal barrel which has a bottom *b* folded in to the bottom edge of the barrel in the inclined seam *c*. The bottom is perforated at *d* and a filter of char- 30 coal or any other suitable material designated *e* fits in the bottom of the barrel. The filter *f* fits into the top of the barrel, while the barrel cap *g* fits over the top end and is provided with a bubbling orifice *h* and an 35 orifice for the valve stem *i*, which comprises simply a rod running down through this stem with a button *j* at its top. A coil spring *k* tends to keep the rod projected. When one wants a drink he simply presses down 40 on the button *j* and this brings the flap valve *l* down over the orifice through the filter and so chokes the water at this point so it will bubble through the bubbling orifice *h* to allow one to drink.

45 One of the special features of this filter is the adaptability it has for attachment to an ordinary faucet or bib. A comparatively thick and wide rubber washer *m* which has a conical outer surface is forced up over the 50 bib or faucet elbow, a thin metallic washer *n* preceding it on the elbow. This metallic washer has a pair of perforated ears *o* through which are adapted to be drawn the metal straps *p* which are part of the metal 55 that is struck out of the side of the barrel to

provide the orifice to receive the bib or faucet elbow. These straps may be drawn through the slotted ears *o* by any suitable tool such as a pair of pincers until the barrel of the attachment is suitably jammed up on 60 the conical exterior of the rubber washer so as to make it water-tight. The straps may then be bent back to hold them in this position, securing a water-tight fit between the washer and the walls of the barrel orifice. 65 Of course the rubber washer itself has a water-tight fit with the bib or faucet elbow inasmuch as it is initially of smaller diameter than this and has to be stretched in order to fit thereover.

70 What I claim is:

1. An attachment for a faucet, comprising a barrel having a bubbling fountain orifice in its top and an aperture through its side adapted to allow a faucet elbow to enter 75 into the barrel, a rubber washer having a conical exterior adapted to be fitted over the faucet elbow and adapted to engage in said aperture, and a metal washer fitting over the faucet elbow ahead of the rubber washer, 80 and means between the washer and the barrel for drawing the barrel into water-tight relation with respect to the rubber washer.

2. A faucet attachment comprising a barrel having a bubbling fountain orifice and 85 having an aperture through its side adapted to receive a faucet elbow, a rubber washer adapted to fit over the faucet elbow and adapted to engage in the aperture in the side of the barrel, a metal washer engaging 90 on the faucet elbow ahead of the rubber washer, and a strap struck out of the metal of the barrel adapted to engage through the metal washer and be turned back to clamp 95 the barrel into water-tight relation with respect to the rubber washer.

3. An attachment for faucets, comprising a barrel provided with an opening in its side and adapted to fit on a faucet, means for securing said barrel over the elbow and packing 100 the space between the opening and the elbow, said barrel provided with an orifice in its bottom to allow the flow of water therethrough and a bubbling orifice in its top, and a valve in the form of a flap and 105 a rod passing through the top of the barrel by which the same may be controlled, said flap when pressed against the bottom orifice serving to choke the water and cause it to bubble through the bubbling orifice.

4. An attachment for faucets, comprising a barrel adapted to fit over a faucet having an aperture in its lower end and a bubbling orifice in its top, a flap valve comprising a flap, a rod running through the top of the barrel, and yielding means for normally keeping the rod projected upwardly, the

said flap thereby allowing the water to flow through the bottom orifice of the barrel but when pressed down causing it to choke the bottom of the orifice thereby causing the water to bubble through the bubbling orifice. ¹⁰

In testimony whereof I affix my signature.

FRANK P. WILLIAMS.
